(57) **CLAIM**

The ornamental design for a vehicle front bumper, as shown and described.

DESCRIPTION

FIG. 1 is a front perspective view of a vehicle bumper cover from the left side thereof showing my new design;
FIG. 2 is a view similar to FIG. 1 from the right side of the vehicle bumper cover of FIGS. 1 and 2;

FIG. 3 is a front perspective view of the vehicle bumper cover of FIGS. 1 to 3; and,

FIG. 4 is a right side elevational view of the vehicle bumper cover of FIGS. 1 to 3, the left side view being a mirror image thereof.

The rear of the design is not being claimed as part of the design.
